UNITED STATES PATENT OFFICE.

HAROLD A. SWAN, OF CORONADO, CALIFORNIA.

PORTABLE BELT SANDER.

Application filed December 31, 1924. Serial No. 759,150.

The present invention relates to a belt sander and has for its prime object to provide a portable device of this nature possessing a simple, efficient, and compact structure, 5 one which is reliable in operation, inexpensive to manufacture, durable, strong, and well adapted to the purpose for which it is designed.

The device also contemplates the construction of a device which can be readily carried from place to place by a person and put into engagement with the work. The device is to be operated by means of an electric motor conveniently housed in its structure.

With the above and numerous other objects in view as will appear as the description progresses, the invention resides in certain novel features of construction, and in the combination and arrangement of parts as 20 will be hereinafter more fully described and claimed.

In the drawing:

Figure 1 is a side elevation of the sander embodying my invention,

Figure 2 is a vertical section taken there-through,

Figure 3 is a horizontal section taken substantially on the line 3—3 of Figure 1 looking downwardly,

Figure 4 is a vertical section taken transversely through the device and substantially on the line 4—4 of Figure 2,

Figure 5 is a fragmentary top plan view of the pressing device,

Figure 6 is a fragmentary side elevation thereof, and

Figure 7 is an enlarged detail sectional view showing the manner in which the brusher is carried by the frame.

Referring to the drawing in detail it will be seen that the frame A of the sander is constructed with a body or upper plate 1 attached to which are the sides 2 which depend therefrom. These sides are provided

with extensions 3 connected by handle 4 of the plate 1, in order that the same may be grasped in the hand. A shaft 6, which is the shaft of an electric motor 7, is journaled in the side members 2 of the frame, and a roller

12 is rotatably mounted between the said side members 2 and is driven from the shaft 6 through the medium of any suitable system

of gearing indicated in general by the numeral 13, the roller 12 being covered by frictional material such as rubber, as indicated by 55 the numeral 17.

An idle roller 18 is journaled on an axle 19 and is also covered with a sheet of frictional material 17. This idle roller 18 is mounted on the axle 19 by means of bearings 60 20. The axle 19 extends through openings 21 in the sides of the frame. On each side of each opening there is provided an ear through which is threaded a screw 24. These screws engage the sides of the ends of the axle and by proper adjustment the distance of idle roller 18 from the driven roller 12 65 may be varied for tensioning the belt sander 25 trained thereover.

A presser casing 26 is movable between the lower portions of the sides 2 and the rollers 12 and 18. This casing is provided with threaded apertured extensions 28. The sides 2 are provided with inwardly extending projections 29 located above the apertures in extensions 28. Thumb screws 30 are threaded through the extensions 28. Springs 31 are disposed about these screws 30 between the extensions 28 and projections 29 of the sides 2 so as to normally hold them separated from 80 one another, the limit of this separation being controlled by the screws 30.

This presser casing 26 has disposed thereabout across its bottom a Brussels carpet strip 32 held in place by plates 33. At the ends 85 of this casing there are provided grooves for receiving vertically disposed ribs 34 on the inner faces of sides 2. The springs 31 tension this presser casing against the lower run 90 of the belt 25 and hold it into engagement with the work upon which the device is being used.

Angular brackets 37 are mounted on the sides of the casing 26 and hold a series of studs 38 formed of flexible frictional material such as rubber and are of sufficient length to extend a little below the belt as is illustrated clearly in Figure 2. Thus when the belt is engaged with the work the studs are engaged with the support upon which the work is located and prevent the sander from movement while it is being held in engagement with the work. In some cases it is evident that these studs will engage the

work itself when it is of a broad nature. I have also found that this device may be inverted and the handle 5 held in a vice and the work applied to the run of the belt 5 sander.

While the preferred embodiment of my invention has been described in detail, it will be understood that I do not wish to be limited to the particular construction set forth, 10 since various changes in the form, materials, proportions, and arrangement of parts, and in the details of construction may be resorted to without departing from the spirit and

scope of the invention as hereinafter claimed or sacrificing any of its advantages. 15

Having thus described my invention, what I claim as new is:

A device of the class described including a frame, a pair of rollers journaled in the frame, a belt sander trained over the rollers, 20 means for rotating one of the rollers, and a series of flexible frictional studs positioned at the sides of and depending below the active run of the belt sander.

In testimony whereof I affix my signature.
HAROLD A. SWAN.
